UNITED STATES PATENT OFFICE.

THOMAS B. WILKINSON, OF LOS ANGELES, CALIFORNIA.

OIL-CAN.

No. 866,546.

Specification of Letters Patent.

Patented Sept. 17, 1907.

Application filed May 16, 1906. Serial No. 317,111.

To all whom it may concern:

Be it known that I, THOMAS B. WILKINSON, residing in Los Angeles, in the county of Los Angeles and State of California, have invented a new and Improved Oil-5 Can, of which the following is a specification.

My present invention is in the nature of an improved oil can of that type in which means are provided for forcibly ejecting the oil through the discharging nozzle, and it primarily has for its object, to provide an 10 oil can of the character described, of a simple and economical construction, in which the several co-operating parts are so combined as to positively direct the flow of the oil to the induction or feed end of the pumping cylinder at any angle or tilt of the can, and the several parts so designed that they can be readily assembled or disconnected as desired.

Generically my present invention comprehends a can having a suitable filling opening, a detachable nozzle and a pumping mechanism contained within 20 the can, actuated under spring action for the infeed of the oil, and hand pulled for ejecting the oil, and means for so effectively packing the plunger rod that escape of oil around it is positively overcome.

In its more complete nature, my present invention 25 includes a special construction of pump devices comprising a pumping cylinder open at the inner end, a piston operating in said end, an induction valved feed tube and a valved ejection tube, (the latter discharging into the can nozzle), located between the outer 30 closed end of the cylinder and the piston, and a handle for actuating the pump under a pulling action.

In its more subordinate features my invention consists in certain details of construction and combination of parts, all of which will hereinafter be fully explained, 35 specifically pointed out in the appended claims and illustrated in the accompanying drawing, in which:

Figure 1, is a perspective view of my improved oil can, parts of the can body being broken away to the more clearly illustrate the internal construction. Fig. 40 2, is a longitudinal section of the can, the several parts being at their normal position. Fig. 3, is a similar view, the parts being at their fluid ejecting position. Fig. 4, is a horizontal section on the line 4—4 on Fig. 2. Fig. 5, is a detail view of the stuffing box hereinafter referred to, 45 and Fig. 6, is a cross section on the line 6—6 on Fig. 2.

In my present form of oil can, the body 1 is of the standard shape and has the usual neck 2 to receive the detachable discharge nozzle 3, it also having the capped filling opening 4. About midway its length is mounted 50 the pump cylinder 5 projected across the body 1 with its inner end stopped short of the adjacent side of the can, and open, the reason for which will hereinafter appear. The cylinder 5 has its outer end fixedly fitted in the annular groove 6 of a stuffing box 60, which is 55 suitably secured to the side of the can by soldering, or otherwise. The box 60 has a central aperture 61 for

the passage of the plunger or pull rod 7, upon which is filled a packing ring or washer 8 held in the socket x, formed within the pendent flanges 62 of the box, and with which engages the metal washer 9, loosely mounted on the plunger or pull rod 7, and held pressed against the packing 62 by the spring 10 mounted on rod 7 and with its outer end seated against the piston, as clearly shown in Figs. 2 and 3.

By providing a stuffing box arranged as shown, the 65 rod is held tightly to its proper position within the cylinder and the packing 8, when the piston is operated, is compressed tightly about the said rod and thereby forms such a tight joint that leakage of the oil through the stuffing box is positively overcome.

By having the outer end of the cylinder open, provides for a full force action of the spring in returning the piston to its outermost position, since were the said end closed, a vacuum would occur in front of the piston which would prevent the full back force of the spring. 70

The piston consists of two inverted cup shaped members 80—80 or a number of leather washers or other suitable material to the desired thickness to form good suction held in position by the nuts 81—81 that engage the threaded outer end of the rod 7 and the washers 80 82—82.

12 designates an induction tube that connects with the cylinder near its inner or head end running diagonally downward to the lower side of can at the bottom and carries an inwardly opening flap or ball valve 13, 85 and 14 designates the discharging tube of the same diameter as tube 12, which connects with the cylinder opposite the discharge of the tube 12, and extends upwardly and discharges into the intake end of the ejection nozzle, and at its upper end it has an upwardly 90 opening flap or ball valve 15, said valve 15 and the valve 13 being suitably weighted to insure a quick closure action thereof under the suction action of the pump piston, and to provide for conveniently removing the valves for repairs if necessary, they may be threaded into the ends of their respective tubes.

The rod 7 is joined to a pull member 17 whose opposite ends are guided in the grooves 18 formed on the inner sides of the portions 18^a of the can handle, as best shown in Fig. 6.

From the foregoing taken in connection with the accompanying drawing, the complete structure and the operation thereof will be apparent. The can is handled the same as the standard oiler, and when desired to eject the fluid, the operator after properly placing the nozzle, with finger action, pulls out the rod 7, which causes the supply within the cylinder and the tube members to flow up through the discharging tube, the pressure in the other tube holding the check valve thereon closed, and as the finger pressure is released, 110 the spring force relieves the piston, which under suction action, draws in a new oil supply up the induction

tube, the valve therein opening, while the valve in the upper tube closes under the vacuum now created below it.

Having thus described my invention, what I claim and desire to secure by Letters Patent, is:

1. The combination with the can body, the cylinder therein provided near one end with a valved feed tube and a discharging tube, a piston in the cylinder whose rod extends through the can side, a stuffing box for the rod having a pocket, and which includes a packing loosely fitted on the rod, and a spring on the rod, one end of which bears on the piston and the other against the packing, for the purposes described.
2. In an oil can of the character described, a stuffing box for the piston pull rod, and a packing held in said box, and means on the rod for compressing the packing on the rod as the rod is pulled out, as set forth.
3. In an oil can of the character described, the combination of a cylinder projected transversely from one side of the can, whose inner end is open, a valved intake tube that projects downwardly from the cylinder, a valved off-take tube that projects upwardly therefrom and dis-

charges into the can nozzle, and the operating piston in the open end of the cylinder having its rod projected outside the can and guided on the can handle.

4. The hereinbefore described improved oil can comprising in combination with the can body, its nozzle, and handle, the latter having guide grooves; of the open ended cylinder secured to one side of the can and projected inwardly thereof, a discharge tube and suction tube that communicate with the cylinder near its closed end, the discharge tube extending up into the entrant end of the nozzle and provided with a back check valve, the suction pipe extending down to near the bottom of the can and having a back check valve in its end, a piston working in the open end portion of the cylinder and having a rod that projects through the can side, a pull member on the outer end of the rod whose ends engage the guide grooves in the can handle, a stuffing box for the rod including a packing ring and a spring disposed on the rod, one end of which bears against the aforesaid packing and the other end against the piston, as set forth.

THOMAS B. WILKINSON.
